DOOR HINGE

John P. Doman, Los Angeles, Calif., assignor to
Victor P. Doman, Los Angeles, Calif.

Application March 3, 1944, Serial No. 524,872

1 Claim. (Cl. 16—180)

1

This invention relates to hinges and more especially to hinges employed in doors and the like.

An object of the invention is to provide a simple, practical and inexpensive hinge of the character described.

Another object is to provide an improved door type hinge having concealed spring means and concealed means for resisting closing movement of the door.

A further object is to provide in a hinge of the character described improved adjustable means for resisting closing movement of the door adapted also to hold the door in one of several open positions and to provide stop means for the same.

Other objects and advantages will appear and be brought out more fully in the following specification, reference being had to the accompanying drawing wherein:

Fig. 1 is an elevation view of a hinge embodying my invention showing same applied to a door in closed position.

Fig. 2 is a top view of the same.

Fig. 3 is a view similar to Fig. 1 showing the door in open position, and

Fig. 4 is a sectional view taken along the line 4—4 of Fig. 3.

Fig. 5 is a view similar to Fig. 4 showing a modification.

Referring more particularly to the drawing I show a hinge having butts 10 and 11, respectively secured within suitable recesses in a jamb 12 and door 13 as by screws 14, suitable screw holes 15 being provided in the butts therefor. Butt 10 is provided with a pair of bearing portions 16 and butt 11 is provided with a plurality of bearing portions 17 interfitting therewith and rotatable with respect thereto by means of bearing pin 18 which interconnects the same. Butt 10 has an aperture 19 and butt 11 has an aperture 20 within which are secured respectively tubular members 21 and 22. A composite spring 23 is disposed within tubular members 21 and 22 and comprises an elongated coil 24 within which is a smaller coil 25, coils 24 and 25 being wound righthanded and lefthanded respectively, by which construction and arrangement a composite spring is provided which is flexible and which will have a uniform bending portion which will not be localized at a point which would otherwise result in an early breaking of the spring in use. Tubular member 22 is provided with apertures 26 in the wall portion thereof in which is positioned a pin 27 which passes through and

2

engages coils 24 and 25 by which the end portion of the spring 23 is secured within tubular member 22, it being clear that the opposite end portion of spring 23 is slidable in tubular member 21.

5 The door movement resisting means of my invention will now be described. One of the bearing portions 16 of butt 10 is provided with a plurality of longitudinal grooves 28, and a pair of strap spring members 29 and 30 are secured to butt 11 by a bolt 31 having a countersunk head 32 and a lock nut 33 so arranged that the tension of springs 29 and 30 may be increased or decreased by a screw driver applied to head 32 which is accessible when the door is in open position. Springs 29 and 30 are arcuately shaped for as shown, and spring 29 has a lip portion 34 for frictional engagement in grooves 28 of bearing portion 16. If desired, I may provide on bearing 16 a stop member 35 to limit the open movement of the door.

10 The operation of the invention should be clear from the foregoing description. The flexure of composite spring 23 is such that when the door is swung to the open position shown in Fig. 4 15 the spring reaction will swing the door back to closed position, the free end of the spring sliding in tubular member 21. The engagement of lip 34 of spring 29 with the grooves 28 is such as to resist this turning movement of the door, 20 and the adjustment of the frictional engagement of spring 29 may be such, if desired, as to retain the door in any position wherein lip 34 is engaged with one of the grooves 28. Abutment 35 is such as to permit the end of spring 29 to 25 engage therewith and limit the movement of the door in the open position.

It will be understood that the features of my 30 invention may be employed in a hinge structure independently of each other. For instance, I may 35 provide a hinge employing the means for resisting closing movement of the door, or I may provide a hinge having only the spring closing means without the means to resist the closing movement. Also I may provide other means of resisting closing movement of the door or to hold the same in open position.

In Fig. 5 I show a modified form of means for holding the door in open position. In this figure I show a hinge having butts 10 and 11, butt 10 40 having a tubular member 21a similar to tubular member 21, however having a plurality of internal beads 21b in the bore thereof. A spring 23a similar to spring 23 is slideable in member 21 but having however a somewhat shorter length 45 so that when the door is in open position as

shown in Fig. 5 the end of spring 23a is spaced from the end 40 of member 21a. A resilient U-shaped member 36 is secured as by a screw 37 to the end of spring 23a and has a plurality of grooves 38 in the arm portions thereof which engage beads 21b and hold the spring from sliding in member 21a and closing the door by its normal tendency to straighten itself out which is the normal closing procedure. Member 36 has abutments 39 which engage the end 40 of member 21a and serve as an opening stop for the door.

While I have shown my invention applied to a door and jamb, it will be understood that the invention may be applied to any type of door or hinged window such as French type doors, casements, transoms, gates, and the like.

Having described my invention what I claim is:

In a hinge for a door as described, a pair of butts having interfitting bearing portions and a bearing pin, a resilient element extending through apertures in said butts to cause closing movement of the door, each said butt having a tubular housing portion for a portion of said resilient element, said resilient element being secured to one of said housing portions and freely

slidable in the other of said tubular housing portions, said element comprising a coiled spring having a second coiled spring therewithin, the coil windings of said springs being oppositely directed.

JOHN P. DOMAN.
